UNITED STATES PATENT OFFICE.

BRUCE DOUGAN, OF ST. LOUIS, MISSOURI.

PENCIL SHARPENER.

Application filed June 21, 1928. Serial No. 117,411.

This invention relates to a certain new and useful improvement in pencil-sharpener and has for its chief object the provision of a sharpener for the purpose stated that is simple, compact, and durable in form and structure, that may with an even, steady, smooth, and natural movement be easily and conveniently operated in economically sharpening the pencil, and which is exceedingly efficient and satisfactory for use wherever found applicable.

My invention has for a further object the provision of a pencil-sharpener of such construction that a single reciprocating operating stroke in one direction at an easy, moderate speed, will impart a sufficiently high speed at the cutters to sharpen the pencil, and a single stroke in the opposite or reverse direction will reverse the rotation of the cutters and tend to expel the pencil from the cutters.

Many other objects and advantages of the construction herein shown and described will be obvious to those skilled in the art to which this invention appertains, from the disclosures herein given.

To this end, my invention resides in the novel features of form, construction, arrangement, and combination of parts herein shown and described and pointed out in the claims.

In the accompanying drawing, wherein like reference characters indicate like or corresponding parts throughout the views,—

Figure 1 is a side elevation of a pencil-sharpener embodying my invention, certain of the parts being broken away in order to show the invention more clearly;

Figure 2 is a top plan view of the sharpener;

Figure 3 is a sectional view, taken approximately along the line 3—3, Figure 1; and

Figure 4 is a sectional view, taken approximately along the line 4—4, Figure 2.

Referring now more in detail to the drawings, wherein I have illustrated a preferred embodiment of my invention, there is shown a pencil-sharpener, and means for mounting the same in a fixed position, so that the same may be conveniently used whenever desired. The mounting or supporting frame 1 may be of any desired size and thickness of material, and preferably has feet 2, preferably apertured, as at 3, for the insertion of fastening means, whereby the frame may be anchored to a desk, table, or other rigid structure or

foundation. Adjacent the top of the frame, there is provided a horizontally extending guideway 4, through which a rack bar 5 may be slidably reciprocated, for purpose shortly appearing.

Secured to the frame 1 by any suitable means, as by screws 6, is a frame-work 7 for supporting the rotary spiral cutters 8. These sharpeners or cutter elements 8 are rotatably journaled in inclined relation to each other in a carrier 9 in turn journaled for rotation on the frame 7 and having a pencil-receiving aperture 10 longitudinally disposed therethrough, whereby, when the pencil is inserted into the opening 10, the cutters 8 will engage therewith. A housing 11 may be hung over the several cutters, so as to receive and hold any cuttings from the pencil, the housing being easily removable, so that the same may be emptied from time to time.

Each of the cutter elements 8 has a pinion 12 secured thereto, which pinions mesh with a ring gear 13 fixed to the frame-work 7 and stationary therewith, so that, when the carrier 9 is rotated about its own axis, the cutters 8 carried by the carrier 9 and rotated bodily in unison therewith, will each rotate about its individual axis.

The carrier 9 has a relatively small gear 14 fixed to its shaft 15, as shown, which shaft preferably extends through and has a bearing in the supporting frame 1, the gear 14 being disposed and concealed within a suitable recess formed in the frame 1, as shown in Figures 1 and 3. A gear 16, preferably larger in diameter than the gear 14 and meshing therewith, is mounted upon a stub shaft 17, so as to lie within a suitable recess provided in the frame 1, said gear 16 having its teeth extending into the guideway 4 so as to mesh with the teeth of the rack member 5. Thus it will be seen that a comparatively slow speed of rotation of the gear 16 will rotate the gear 14 at a much higher speed, whereby the cutter elements 8 will be driven at relatively high speed.

The gearing is so arranged that the cutters 8 will rotate in a cutting movement relatively to the pencil engaged thereby preferably only when the rack 5 is moved in one direction, preferably rearwardly, or toward the operator, this movement being a pulling movement of the rack. Such a rearward pull upon the rack is a natural, easy movement for the operator and is accomplished

with a steady, smooth, even pull. Such an even, high-speed cutting movement at the cutters, resulting from the rearward pull of the rack, will sharpen the pencil neatly, 5 quickly, and efficiently. If the gearing were so arranged that the forward push of the rack were to operate the cutters, the natural tendency of the one arm of the operator would be to thrust the rack-bar 5 forwardly 10 as quickly as possible and at an uneven speed while at the same time the tendency of the other arm of the operator would be to thrust the pencil forwardly into the tool and between the cutters 8, with the result that the 15 exposed point of the pencil would be broken and the pencil quite apt to be unnecessarily cut away before a finished point were obtained.

A cushion stop 18 may be provided at the 20 forward end of the rack, as shown, for engagement with the frame 1 to both limit the rearward movement or reciprocation of the bar 5 and to take up any resulting shock.

Preferably also a closure plate 19 is provided inwardly of the ring gear 13 to prevent the entrance into the gearing of the tool of pencil clippings and the like which might interfere with or retard proper operation of the tool.

From the foregoing description, it will be 30 seen that I have provided a pencil sharpener that may be operated with but a single rearward stroke of the rack member, such a stroke being given in a natural, normal manner at an even, steady speed, causing the cutters that engage the pencil to rotate at a high, even speed, sharpening the pencil quickly and neatly without injury to the pencil. Furthermore, it will be obvious 35 that by the reverse movement of the rack-bar, the spiral cutters will be reversed in rotation, and should the point of the pencil be retained in the cutters, will tend to expel or loosen or release the pencil from the 40 cutters.

Having thus described my invention, it is obvious that various modifications may be made in the same without departing from the spirit of my invention; hence I do not 50 wish to be understood as limiting myself to the exact form, construction, arrangement and combination of parts herein shown and described, or uses mentioned, except as limited by the claims.

Having thus described my invention, what I claim and desire to secure by Letters Patent is:

1. In a pencil sharpener, in combination, 60 a supporting frame having a slide-way, a plurality of cooperating spiral cutters mounted for rotation on the frame, and means for effecting rotary movement in unison of the cutters, said means including a gear mounted for rotation on the frame and having driving connection with the cutters,

and a rack-bar arranged for reciprocating movement in one direction in said slide-way and having meshing engagement with said gear to operate said cutters to sharpen a pencil inserted therebetween, and for reciprocation in the opposite direction to reverse the rotation of the spiral cutters to release or expel the pencil therefrom. 70

2. In a pencil sharpener, in combination, 75 a supporting frame having a slide-way, a plurality of cooperating spiral cutters mounted for rotation on the frame, and means for effecting rotary movement in unison of the cutters, said means including a gear mounted for rotation on the frame and having driving connection with the cutters, 80 and a rack-bar arranged for limited reciprocating movement in one direction in said slide-way and having meshing engagement with said gear to operate said cutters to sharpen a pencil inserted therebetween, and for limited reciprocation in the opposite direction to reverse the rotation of the cutters to release or expel the pencil from the 85 cutters, the said rack-bar having a handle at one end and a stop at its other or free end. 90

3. In a pencil sharpener, in combination, 95 a supporting frame, a plurality of cooperating spiral cutters, and means for effecting rotary actuation in unison of the cutters, said means including a cutter-carrier mounted for rotation on the frame, a gear on the carrier, a second gear mounted for rotation on the frame and meshing with the first gear, the frame having a slide-way and a 100 rack-bar arranged for reciprocation in one direction in said slide-way and having meshing engagement with the second gear to rotate said cutters in one direction to sharpen a pencil, and for reciprocation in the opposite direction to reverse the rotation of the spiral cutters to release or expel the pencil from the 105 cutters. 110

4. In a pencil sharpener, in combination, 110 a supporting frame a plurality of cooperating rotary spiral cutters, a carrier for the cutters mounted for rotation on the frame, the cutters being adapted for rotation in unison about the axis of the carrier on rotation of the carrier, a gear on the carrier, a second gear mounted for rotation on the frame and meshing with the first gear, the frame having a slide-way above and in the plane of the second gear, and a rack-bar arranged for reciprocation in one direction in said slide-way, and having meshing engagement with the second gear, to rotate said spiral cutters in pencil-sharpening direction, and for reciprocation in the opposite direction to reverse the rotation of the cutters to release or expel the pencil from the cutters. 115 120

5. In a pencil sharpener, in combination, 125 a supporting frame, a large gear journaled for rotation on the frame, the frame having 130

a slide-way disposed above and in the plane of the gear, a rack-bar arranged for reciprocation in said slide-way and having meshing engagement with the large gear, a carrier 5 journalled for rotation upon the frame, a second, smaller gear on the carrier meshing with the larger gear, a plurality of spiral cutters carried for rotation by the carrier, pinions on the cutters, and a stationary ring-
10 gear meshing with said pinions, whereby a

single reciprocation of said rack-bar in one direction rotates said cutters at high speed in a cutting direction, and a reciprocation of the rack-bar in the opposite direction reverses the rotation of the spiral cutters to 15 expel or release the pencil therefrom.

In testimony whereof I have signed my name to this specification.

BRUCE DOUGAN.
